UNITED STATES PATENT OFFICE.

MARINE R. WARDEN, OF CHICAGO, ILLINOIS.

WAVE-MOTOR.

1,096,332.

Specification of Letters Patent. Patented May 12, 1914.

Application filed October 29, 1913. Serial No. 793,063.

To all whom it may concern:

Be it known that I, MARINE R. WARDEN, a citizen of the United States, residing at Chicago, in the county of Cook and State of Illinois, have invented certain new and useful Improvements in Wave-Motors, of which the following is a specification, reference being had to the accompanying drawings.

This invention relates to new and useful improvements in wave or surf motors and the primary object of the invention is to provide a device of this character which may be placed on the beach of a body of water to generate power under an even motion to be used for any desired purpose.

A further object of the invention resides in providing a device which will be actuated by the waves or swells as the same are directed inwardly on the beach and also as the water recedes.

Still another object of the invention resides in providing a device which is simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawings forming a part of this application, Figure 1 is a side elevation of the device. Fig. 2 is a longitudinal section therethrough. Fig. 3 is a perspective view of a slightly modified form of the invention showing the bucket member in a position to receive the wave moving in one direction. Fig. 4 is a similar view showing the bucket disposed in a position to receive a wave moving in an opposite direction; and Fig. 5 is a perspective view of the bucket in a feathered or inoperative position.

In describing my invention I shall refer to the drawings in which similar reference characters designate corresponding parts throughout the several views and in which—

1 indicates a supporting device of any desired character, composed primarily of four vertical posts or piers which are arranged in pairs and disposed on a beach of a body of water. Mounted for rotation in the pairs of posts, are the shafts 2, carrying thereon at the ends thereof the sprockets 3 and extending over the pairs of sprockets

are the endless link chains 4. Connecting the chains 4, at predetermined points in the length thereof, are a plurality of bars 5 and these bars are connected to the links of the chain by passing through the ends of said links, taking the place of the usual connecting pins therefor. Nuts or t' e like are applied on the outer ends of said bars 5 to secure the same in place and it will be seen that in view of the particular manner in which said bars are applied to the chain, the same will afford no obstruction whatsoever in the operation of the device, as said chains are passed over the sprocket wheels.

Hingedly mounted on each of the rods or bars 5, is a plate 6 which may be formed of wood, metal or any other desired material and connecting the outer free edge of each plate with the adjacent bar or rod of the pairs, are the flexible connections 7. These flexible connections, obviously limit the swinging movement of said plates 6 in one direction. In the drawings, I have shown but a pair of such plates in connection with the endless chains 4, but it will be understood that as many may be provided as are desired.

A device constructed in the manner described, is placed on a beach of a body of water so that the chains are immersed below the surf and as the wave rolls inwardly, the same will contact with the plate or plates 6 on the upper reaches of the chains 4 to force the same upwardly, as shown in Figs. 1 and 3. These plates 6 will be forced in such position until the flexible connections 7 are drawn taut, whereupon said plates will offer considerable resistance to the incoming wave. On the other hand, the plate or plates 6 on the lower reaches of the chains 4 will be swung in a direction to slacken the connections 7 and thus the latter plates afford little or no resistance whatsoever. In view of the resistance which is offered by the plate or plates in connection with the upper reaches of the endless chains, it will be seen that as the waves are directed inwardly, the chains will be actuated and cause the sprockets 3 to be rotated in a direction as shown by the arrow. As the waters on the beach recede, the same will be directed against the plate or plates in connection with the lower reaches of the endless chains 4 and said latter plates will be directed upwardly, if made of floating material, and offer resistance thereto. The plate or plates 6 in con-

connection with the upper reaches of the chains will, however, be directed downwardly and offer little or no resistance to the receding waters. The resistance offered by the lower plate or plates will, obviously cause the chains to be drawn in the same direction as operated in the first instance, and thus the sprocket wheels 3 will be rotated continually in the same direction. It will be appreciated that any desired connecting means may be engaged with the shafts 2 upon which said sprockets are mounted, whereby to supply power to any desired mechanism, (not shown).

In Figs. 3, 4 and 5, I have shown a slightly modified form of the invention consisting of an improved bucket formation to be applied on the endless chains of the device. In this modified form, endless chains 8 are provided and mounted in connection with sprockets on a support as in the first mentioned form and said chains are connected together by means of rods or bars 9. This form of bucket or means for offering resistance to cause the chains to be actuated, consists of a plate section 10 which is hinged to one of the bars 9 and to the outer edge of the plate 10 is also hinged an additional plate 11. The latter plate is of slightly greater length than the plate 10 and the outer free edge of the latter is connected to the adjacent bar or rod 9 of the plurality of rods by means of the flexible connections 12. Plates 13 are secured to the outer side edges of the plate 10, said plates 13 being substantially V-shaped in design so that one arm of each of the same, in any position of the device, receives a projecting portion of the plate 11 in resting engagement therewith. In Fig. 3, I have shown the manner in which this bucket formation will appear on the upper reaches of the chain as the waves are directed inwardly toward the beach and, in Fig. 5, I have shown the position thereof on the lower reach when feathered to offer the least amount of resistance to the inwardly flowing waters. In Fig. 4, I have shown the position of a bucket on the lower reach of the chain, disposed in a position to offer resistance to the receding waters. The manner of operation of the device embodying this modified form is otherwise the same as the first mentioned form, so that the same will doubtless be understood from the above description of the construction of the device.

From the foregoing it will be seen that I have provided a device which is simple and durable in construction, inexpensive to manufacture and one which will be very efficient and useful in operation, and while I have particularly described the elements best adapted to perform the functions set forth, it is obvious that various changes in form, proportion and in the minor details of

construction may be resorted to without departing from the spirit or sacrificing any of the principles of the invention.

Having thus described this invention, what is claimed is:—

1. In a wave motor, a support, a plurality of sprocket wheels rotatably mounted thereon and arranged in pairs, endless chains connecting the pairs of sprocket wheels, a plurality of transverse bars connecting said pairs of chains at predetermined points in the length of the latter, resisting members pivotally carried on certain bars adapted to swing to lie either above or below the adjacent portions of the chains, each member consisting of a pair of plates hinged together, means associated only with the plates of each resisting member to limit the swinging movement of the same with respect to one another, and flexible connecting means between the free end of the outer plate section of each pair of plates and the adjacent transverse rod whereby to limit the swinging movement of the resisting member.

2. In a wave motor, a support, a plurality of sprocket wheels rotatably mounted thereon and arranged in pairs, endless chains connecting the pairs of sprocket wheels, a plurality of transverse bars connecting said pairs of chains at predetermined points in the length of the latter, resisting members pivotally carried on certain bars and each member consisting of a pair of plates hinged one to the other, means carried on the side edges of the one plate section adapted to coöperate with the other plate section of the pair of hinged together plates, whereby to limit the swinging movement thereof with respect to one another, and additional means to limit the swinging movement of the complete resisting member on the endless chains.

3. In a wave motor, a support, a plurality of sprocket wheels rotatably mounted thereon and arranged in pairs, endless chains connecting the pairs of sprocket wheels, a plurality of transverse bars connecting said pairs of chains at predetermined points in the length thereof, bucket-like resisting members pivotally carried on certain bars and each member consisting of a pair of hinged together plates, the outer hinged plate section being of greater width than the inner hinged plate section, means in connection with the last mentioned plate section of said hinged together plates coöoperating with the projecting portion of the other hinged plate section to limit the movement of said plate sections with respect to one another, and means to limit the swinging movement of the complete resisting member on the chains.

4. In a wave motor, a support, a plurality of sprocket wheels rotatably mounted thereon and arranged in pairs, a pair of endless chains extending over the pairs of sprocket

wheels, a plurality of transverse bars connecting said pairs of chains at predetermined points in the length thereof, bucket-like resisting members pivotally carried on 5 certain bars and each bar being composed of a pair of hinged together plate sections, the outer hinged plate section being of slightly greater length than the inner hinged section and having its ends projecting 10 beyond the ends of the latter, V-shaped plate members secured to the ends of the inner hinged section, the arms thereof being adapted to contact with the faces of the pro-

jecting portions of the outer hinged plate section to limit the swinging movement of 15 the latter with respect to the inner hinged section, and additional means for limiting the swinging movement of the complete resisting member on the chains.

In testimony whereof I hereunto affix my 20 signature in the presence of two witnesses.
